Primary Examiner — Kathleen L Jones*Assistant Examiner* — Jasmine L Comedy(74) *Attorney, Agent, or Firm* — Dickinson Wright PLLC(57) **CLAIM**

The ornamental design for a hand held light with a kickstand, as shown and described.

DESCRIPTION

FIG. 1 is a perspective view of a hand held light with a kickstand according to an aspect of the present disclosure; FIG. 2 is a front view of the hand held light of FIG. 1; FIG. 3 is a right side view of the hand held light of FIG. 1; FIG. 4 is a left side view of the hand held light of FIG. 1; FIG. 5 is a rear view of the hand held light of FIG. 1; FIG. 6 is a top view of the hand held light of FIG. 1; FIG. 7 is a bottom view of the hand held light of FIG. 1; and, FIG. 8 is a perspective view of the hand held light of FIG. 1 with the kickstand an alternate position.

The dash-dash broken lines shown in the drawings represent portions of the hand held light with a kickstand that form no part of the claimed design. The dot-dash broken lines represent boundaries that form no part of the claimed design.
